CLAIM

The ornamental design for an incubator medical apparatus, as shown and described.

DESCRIPTION

1. Incubator medical apparatus

1.1 : Perspective

1.2 : Perspective

1.3 : Front

1.4 : Back

1.5 : Right

1.6 : Left

1.7 : Top

The broken line showing of portions of the incubator medical apparatus is for the purpose of illustrating environmental structure and forms no part of the claimed design. The bottom view is omitted and forms no part of the claimed design.
